CABLE LUBRICATOR

John Edmund Tonnelier, New York, N. Y.

Application January 24, 1947, Serial No. 723,993

13 Claims. (Cl. 184—17)

1

My invention relates to the lubrication of cables and in particular to means for lubricating the cables of a lift bridge.

In many cable-operated mechanisms, such as lift bridges, wherein a span is lifted at both ends to provide greater clearance for the passage of vessels, the proper maintenance of the cables which are constantly exposed to weather has been an expensive and difficult task. The customary procedure has been to close a bridge to traffic for an extended period of time while hot lubricant has been applied manually as by swabs or brushes. Not only does this manual method compel a lengthy tie-up and rerouting of traffic during the period of the maintenance operation, but droplets of oil are necessarily spilled upon the bridge structure and upon the roadway to the impairment of neatness and safety.

It is, accordingly, an object of my invention to provide improved means for maintaining cables.

It is another object to provide a less costly and more effective means for lubricating the cables of a lift bridge without unduly tying-up the traffic that would normally flow across such bridge.

It is a more specific object to provide means whereby the cables of a lift bridge may be lubricated with substantially no loss of lubricant—so that the safety of the roadway surface may not be impaired.

It is a still more specific object to provide means for quickly and effectively lubricating a plurality of adjacent cables that are staggered so as to lie in different planes.

Other objects and various further features of the invention will be pointed out or will occur to those skilled in the art from a reading of the following specification in connection with the accompanying drawings. In said drawings:

Fig. 1 is a partially sectionalized side view of a portion of a lift bridge incorporating features of the invention;

Fig. 2 is a perspective view of a cable-lubricating device of the invention as applied to the structure of Fig. 1;

Fig. 3 is a vertical sectional view taken substantially in the plane 3—3 of Fig. 2;

Fig. 4 is another sectional view of the lubricating device of Fig. 2, but taken substantially in the plane 4—4 of Fig. 3;

2

Fig. 5 is a plan view of the device of Fig. 2;

Fig. 6 is a view similar to Fig. 4, but with the lubricating device modified so as to permit performance of an additional function; and

Fig. 7 is a partially broken-away plan view of the modified structure of Fig. 6.

Broadly speaking, my invention contemplates the automatic lubrication of cables in a lift bridge or the like in the course of a normal full-up and full-down operation of the lifted span. Lubricant is carried in a bath or reservoir, and a system of rollers dips into this lubricant and applies the same to the sides of the cables, as by a wiping contact therewith. In the specific form to be described, means are provided whereby a single lubricating device may be employed to lubricate a plurality of cables of different spacings from the lubricating device and from each other. Depth of the penetration of lubricant into the cables may be regulated by a thermostatically controlled heater provided in the bath.

Referring to the drawings, my invention is shown in application to the lubrication of a plurality of cables 10, 11 providing the lifting means for one end of a span 12 of a lift-bridge structure. The cables are strung over sheave means 13 journaled near the top of a lifting tower 14 erected near the span end 12. Substantially one-half the weight of the span is offset by a counterweight 15 attached to the other ends of the cables 10 and 11. Lifting of the span may be accomplished by the application of relatively low-power torques to the sheave means 13, as by means of a motor-driven gear engagement (not shown) therewith. In accordance with conventional practice, the cable means 10 and 11 may spread slightly to their points of attachment with the span end 12 and with the counterweight 15.

In accordance with the invention, novel lubricating means may be installed at the top of the tower structure 14 for continuous wiping contact with the cables 10 and 11. In the arrangement shown, a first lubricating device 16 is mounted for lubrication of the cable means 10 to one side of the sheave means 13, and another lubricating device 17 is mounted on the other side of the sheave means 13 to lubricate the cables 11. It will later be clear that, if desired, only one of the lubricating means 16 or 17 need be employed.

and that either device may provide efficient and effective lubrication of both the cable means 10 and 11.

Referring now to Figs. 2, 3, 4, and 5, I show in detail how one of my lubricating means 16 or 17 may be employed in the simultaneous lubrication of a plurality of cables. In the case shown, there are twelve lifting cables more or less aligned in sets of six in two planes diverging more or less in accordance with the divergence for the cables 10 and 11 in Fig. 1. The cables 18, 19, 20, 21, 22, and 23 lie substantially in one of the above-defined planes and are substantially equally spaced from each other. In the other set, cables 24, 25, 26, 27, 28, 29 lie substantially in the second plane and are also equally spaced with respect to each other. Both planes converge to or substantially intersect in a transversely extending line at the points where the cables are tangent to or begin to run over the sheave means 13. The cables 18 through 23 of the first plane are staggered with respect to the cables 24 through 29 of the second plane.

In accordance with the invention, all of the cables in either one of the above-defined planes may be simultaneously lubricated by a single lubricating device. This lubrication is effected through the continuous wiping contact of a plurality of rollers 30 with the cables in such plane. In the form shown, the rollers 30 are formed of substantially the same diameter and are rotatably mounted on the sides of a lubricant bath 31. Also pivotally supported by the bath 31 is another set of rollers 32, substantial parts of which are preferably always immersed in the lubricant carried in the bath 31. The rollers 32 may be supported upon a common shaft and are spaced for peripheral wiping contact with the rollers 30. It will then be clear that upon a lifting operation of the bridge, that is upon a movement of the cables 18-23 with respect to the lubricating bath 31 and its associated elements, the rollers 30 will rotate so as to cause rotation of the rollers 32. The rollers 32 will evenly and continuously wet the peripheries of the rollers 30 with lubricant, and an even amount of lubricant will then be applied to substantially the entire used length of cables 18-23.

It will be appreciated that since the planes in which the two sets of cables 18-23 and 24-29 lie are convergent, there will be a slight lateral motion of these cables upon operation of the bridge. To compensate for this lateral motion at the point of lubrication, the lubricating bath 31 is preferably urged continuously and displaceably against the cables it is lubricating. In the form shown, this constant urging may be effected automatically by mounting the lubricating bath 31 upon a pivotal axis located preferably below the center of gravity of the bath 31 and on the side of the bath 31 away from the cables. The pivotal axis of support may be derived by removable placement of the bath 31 upon a transversely extending shaft or pipe 33, which in turn may be secured and permanently mounted upon a platform 34 or other structure as by means of angle brackets 35 bolted thereto. U-shaped brackets 36 formed with or attached to the bath 31 will clearly permit removable insertion of the bath 31 and of its associated rollers upon the pivotal shaft 33.

It will be observed that for the arrangement shown in Figs. 2 to 5, the roller means 30 are employed for lubricating the cables that are more remote from the lubricating bath 31. For

this purpose, the rollers 30 are preferably of a diameter large enough to permit hub clearance with the adjacent cables which are in the other plane and which are therefore not being lubricated from the bath 31. For a reason which will later be clear, all of the rollers 30 and all of the rollers 32 are spaced from each other by amounts corresponding to the spacing between cables that are to be lubricated, but they are spaced more from one end of the bath 31 than they are from the other end. This additional spacing may be provided by insertion of additional collars 37, 38 upon the shaft 39 forming axial support for the rollers 30, and by a corresponding set of collars or washers 39-40 at one end of the shaft 41 on which the rollers 32 are mounted.

For smooth and even application of lubricant to the periphery of the cable-wetting rollers 30, I prefer that the mounting of these rollers 30 to the bath 31 be accomplished in a manner which will permit these rollers freely to ride upon the primary wetting rollers 32. In the form shown, this freedom is permitted to the rollers 30 by mounting their end bearings 42 in generally upwardly extending grooves, defined by tracks or ways 43 formed in the end of the bath 31 as by brazed strips of angle iron 32. The ways 43 preferably extend generally radially from the pivotal axis for the primary wetting rollers 32 and, if desired, the shaft 41, on which the primary wetting rollers 32 are mounted, may be supported in the bottom of the same ways 43 as employed for the slidably support of the rollers 30. It will be appreciated that with the mounting arrangement described for the rollers 30 and 32, these rollers may be readily removed from the bath as complete unit-handling assemblies tied to their respective mounting shafts 39 and 41.

Also for the purpose of assuring an even flow of lubricant to the cable, I prefer that the rollers 30 be formed with concave surfaces at their peripheries so as to present greater contact surface areas to the cables being lubricated. The rollers 32 are preferably formed with convex peripheries fitting the concave surfaces of rollers 30 to assure smooth application of lubricant on the concave surfaces. In the event that the concave curvature of the rollers 30 may not initially completely conform with the curvature of the cables they are to lubricate, I prefer that the rollers 30 be fabricated of a slightly deformable material. I have found plastic-impregnated and bonded plywood constructions highly satisfactory and of reasonable cost for the fabrication of both the rollers 30 and the rollers 32. It may happen, particularly in the case of rollers 30 of larger diameters, that the efficiency of oil-application to the cables is not as much as may be desired. In such case, I prefer to employ a felt, cloth, or other wick-like liner 30' extending circumferentially in the groove of the roller 30. It will be understood that the efficiency of lubricant-application will then be limited substantially only by the ability of the liner 30' to absorb the lubricant.

Further to assure an even flow of lubricant to the cables and constancy of depth of penetration of lubricant into the cable, it is desirable to maintain the lubricant in the bath 31 at a well-regulated elevated temperature. For this purpose, electric-heater means of conventional construction may be inserted in a fluid-tight chamber 44 extending generally transversely of the bath 31 and preferably at all times in con-

tact with lubricant contained therein. Power of the heater in the tube 44 may be supplied by a conventional flexible connection 45 to a suitable electric power outlet 46.

In order to assure a minimum of dropping or of splashing of oil, particularly when rollers 30 of large radius are employed to lubricate the more remote cables 18-23, I prefer to employ individual gutters 47, which may be detachably secured under the parts of the rollers 30 that project beyond the lip 48 of the bath 31. The gutters 47 may be designed to return substantially all splashed lubricant to the bath 31. If desired, the gutter 47 may be removably attached to the bath 31, as by sliding a suitable projection into a bracket or loop 49 formed on the lip 48.

In accordance with another feature of the invention, the bath 31 may be employed, without removing it from its pivotal support on the platform 34, in the lubrication of the set of cables 24-29 located in the plane nearest the bath 31. For this purpose, another set of cable-wetting rollers 50 may be mounted on the bath 31 in place of the rollers 30. However, in view of the fact that the cables 24-29 are all staggered with respect to the cables 18-23, the primary wetting rollers 32 must be transversely displaced with respect to the positions they assume when employed in the lubrication of cables 18-23. To accomplish this displacement with a minimum of adjustment, the rollers 32 together with shaft 41 to which they are mounted may be removed as a unit from the ways 43, reversed end for end, and again inserted into the ways 43, whereby the spacer washers 39-40 are then located at the opposite end of the bath 31. The cable-wetting rollers 50 are preferably similar in all respects to the rollers 30 except that they are of reduced diameter to accommodate the closer set of cables. As in the case of the rollers 30, the rollers 50 may be mounted on a common axial shaft 51 having spacing washers 52-53 at one end thereof and bearings 54 slidably receivable in the ways 43. It will be appreciated that when using the smaller rollers 50 for lubricating the smaller cables 24-29, there is relatively little projection of the cable-wetting rollers 50 beyond the lip 48 of the bath 31 and that there may, therefore, be no need for drip-catching gutters such as gutters 47 described for use with the rollers 30.

It will be appreciated that I have described a relatively simple mechanism for simultaneously lubricating a number of cables and for performing this function in a minimum of time. It will be clear that but one lubricating device will suffice to lubricate substantially the entire length of cables located in two spaced and diverging planes. However, if but one lubricating device is employed, at least two operations of the bridge may be needed to lubricate all cables. If it is desired to lubricate all cables in a single operation of the bridge, the dual arrangement of lubricators (shown in Fig. 1) may be employed. It will be noted that the employment of lubricating devices on both sides of the sheave means 13 may also permit the lubrication of a more substantial length of the cables. Substantially the entire length of cable running over the sheave (i. e. the flexed length of cable) may be lubricated in this manner.

Viewed in its broader aspects, my invention will be seen to provide a means for substantially reducing the cost of maintaining cables and

structures of the character indicated and for effecting this maintenance in but a small fraction of the time formerly required. The saving in time is reflected in savings in costs as well as in a very material reduction in the time for which the bridge must be closed to traffic.

While I have described my invention in detail for the preferred form shown, it will be appreciated that modifications may be made within the scope of the invention as defined in the claims which follows.

I claim:

1. In a device of the character indicated, a bath for holding lubricant, a first roller pivotally supported by said bath for partial immersion in lubricant held in said bath, and a second roller radially freely slidably supported by said bath generally above said first roller and in wiping contact with an exposed unimmersed portion of said first roller.

2. In a device of the character indicated, a bath for holding lubricant, a first roller pivotally supported by said bath for partial immersion in lubricant held in said bath, a second roller supported by said bath and in wiping contact with an exposed unimmersed portion of said first roller, and generally upwardly extending guide means freely slidably guiding said second roller generally upwardly of said first roller, the axis of said second roller being supported generally horizontally between the axis of said first roller and a generally vertically extending surface to be lubricated, whereby said second roller may freely assume a continuous wiping contact with the surface to be lubricated while maintaining both said rollers in wiping contact.

3. In a device of the character indicated, a bath for holding lubricant, a first roller pivotally supported by said bath for partial immersion in lubricant held in said bath, a second roller supported by said bath and in wiping contact with an exposed unimmersed portion of said first roller, and means for pivotally supporting said bath, whereby said bath when tilted may, of its own accord, urge said second roller into wiping contact with a cable or the like to be lubricated.

4. A device according to claim 3, in which the pivotal axes of said rollers and of said bath are substantially parallel to each other.

5. In a device for lubricating a plurality of cables, a bath for holding lubricant, roller means supported by said bath for partial immersion in lubricant held in said bath and for peripheral wiping contact with said cables, and a pivotal support for said bath for the purpose set forth.

6. In a device for lubricating a plurality of cables, a bath for holding lubricant, first roller means pivotally supported by said bath for partial immersion for lubricant held in said bath, second roller means for peripheral wiping contact with said first roller means and with said cables, and supporting means for supporting said second roller means on said bath, said supporting means including guide means extending generally radially and upwardly from the pivotal axis of said first roller means, said guide means slidably guidingly supporting said second roller means for free radial positioning of said second roller means radially of said first roller means, whereby said second roller means may be urged by its own weight to ride freely on said first roller means.

7. A device according to claim 6, in which heater means are provided in said bath for

maintaining lubricant contained therein at a desired elevated temperature, whereby lubricant applied to a cable by said device may more readily penetrate the cable.

8. In a device for lubricating a plurality of cables spaced from each other and lying in substantially the same plane, a bath for lubricant, first roller means including a plurality of rollers spaced in accordance with spacings of said cables and supported for partial immersion in lubricant in said bath, second roller means comprising a plurality of rollers spaced in accordance with the spacings of said cables and in peripheral wiping contact with the rollers of said first roller means and projecting from said bath for wiping contact with said cables, and means for pivotally supporting said bath to the side of said bath away from the side on which wiping contact with said cables occurs, the pivotal axes of said roller means and of said bath being substantially parallel.

9. In a device for lubricating a plurality of spaced cables, some of which lie in one plane and some of which lie in another plane spaced from said first plane, a bath for lubricant, first roller means for partial immersion in lubricant held by said bath, second roller means for peripheral wiping contact with said first roller means and with the cables in the plane further from said bath, and means for pivotally supporting said bath for tilting toward said cables.

10. In a device for lubricating a plurality of spaced cables, some of which lie substantially in one plane and some of which lie substantially in another plane, said planes intersecting in a line extending transversely of said cables, the two cables nearest transversely adjacent to a first cable in one of said planes both lying in the other of said planes, a bath for lubricant near said other plane, first roller means for partial immersion in lubricant held by said bath, second roller means for peripheral wiping contact with said first roller means and including a roller extending between said two cables into peripheral wiping contact with said first cable, and means for pivotally supporting said bath on the side of said bath away from said cables.

11. A device according to claim 10, in which

5

said bath includes a projecting lip under said roller and extending into proximity with said first cable for catching lubricant dripping from said roller and for returning said lubricant to said bath.

12. A device according to claim 10, in which said roller is formed with a circumferentially extending concave surface of curvature generally in conformity with that of said first cable, and wherein said first roller means includes a circumferentially extending convex surface to fit said concave surface.

13. In a device for lubricating a plurality of spaced cables, some of which lie substantially equally spaced in one plane and some of which lie substantially equally spaced in another plane, said planes intersecting in a line extending transversely of said cables, the cables in one plane being transversely staggered between the cables in the other plane, a bath for lubricant supported to one side of said cables and having a side transversely spanning said cables, said bath being urged toward said cables, roller means including rollers spaced to wipe every other of said cables, means for supporting said roller means on both ends of said bath, and spacer means for spacing said roller means away from one of said ends more than from the other of said ends by an amount corresponding to the transverse spacing between adjacent cables, whereby said roller means may be employed to lubricate the cables in one of said planes in a first operation and the cables in the other of said planes in a second operation.
